(No Model.)

J. H. GUEST.

ELECTRIC RAILWAY SUPPLY SYSTEM.

No. 537,199.

Patented Apr. 9, 1895.

FIG-1. A complex electrical circuit diagram showing multiple parallel branches. The circuit includes various components such as resistors, capacitors, and inductors, connected in a multi-level, multi-phase configuration. The diagram is labeled with terminals T and T' at the top and bottom, and with numbers 1, 2, 3, 4, 5, 6, and letters E , E' , n , m , a , a' , g , g' , b , b' , c , c' , d , d' , h , h' , s , s' , z_0 , and z_1 throughout the network.

FIG-2. A simplified diagram of a single-phase bridge rectifier circuit. It shows a diode bridge connected to a load resistor R and an AC source. The output voltage is indicated by a vector sum of the individual diode drops.

FIG-3. A simplified diagram of a three-phase bridge rectifier circuit. It shows a three-phase AC source connected to a three-phase diode bridge, which is then connected to a load resistor R . The output voltage is indicated by a vector sum of the individual phase voltage drops.

UNITED STATES PATENT OFFICE.

JOHN H. GUEST, OF BOSTON, MASSACHUSETTS.

ELECTRIC-RAILWAY SUPPLY SYSTEM.

SPECIFICATION forming part of Letters Patent No. 537,199, dated April 9, 1895.

Application filed February 20, 1894. Renewed February 2, 1895. Serial No. 537,127. (No model.)

To all whom it may concern:

Be it known that I, JOHN H. GUEST, a citizen of the United States, and a resident of Boston, in the county of Suffolk and State of Massachusetts, have invented a certain new and useful Improved Electric Railway, of which the following is a specification.

My present invention relates more particularly to that class of electric railways in which the working contact or conductor from which the car takes up current is divided into separate sections or contacts that are automatically charged as the car reaches the section and discharged as the car leaves it by means of suitable electric switches that are normally open and when closed connect the said section or working conductor with a suitable supply wire or circuit leading from a proper source of energy.

My invention relates more particularly to those systems wherein a magnet on the car operates upon an armature on the permanent way as the car moves along, and by actuating said armature operates the switch that closes the connection between a supply or line conductor and the insulated working conductor or section of conductor. In the plans heretofore proposed two magnets were employed of respectively opposite polarity, one of which closes and the other of which opens the switch thus requiring a reversal of the polarity of said magnets in order to reverse the direction of travel of the car.

My invention admits of the car running in either direction without reversing the polarity of the magnet or magnets employed, either of which when two are used may serve to set the switches instead of one setting and the other unsetting.

My invention consists in the combination with a magnet on the car and an armature therefor on the permanent way for closing the switch for one section, of means for opening the switch by current flowing to another section when the car reaches the latter.

My invention consists further in the combination of the magnet on the car, a polarized armature and switch for one section, and an electro-magnet for reversing the position of the polarized armature, said electro-magnet being in the circuit of another section.

My invention consists also in the combina-

tion with each section, of a resetting circuit closed therethrough for sections both to the front and rear of said section.

My invention consists further in the special combinations of devices and apparatus hereinafter described, and more particularly stated in the claims.

In the accompanying drawings:—Figure 1 is a general diagram illustrating the principle of my invention. Fig. 2 is an inverted plan view of the cover plate for the box containing the switch for one section of working conductor. Fig. 3 is a side elevation showing more in detail the switch for one section and the arrangement of magnets and current collector on the car.

I will refer first to the devices shown in Fig. 3, premising that the devices themselves may be indefinitely varied in form and construction, the gist of the invention consisting in the combination of circuits and devices each adapted to operate electrically and magnetically as required in the combination.

A is one of the sections of working conductors. This may be and preferably is the cover of a box or section of conduit containing the switches, armatures and coils on the permanent way. The cover may be of iron and flush with the surface of the roadway or otherwise located to be engaged by a current collector borne by the car. The current collector is typified at W, as a wheel working in a frame or bracket supported from above by any part of the car or car truck and adapted to pick up the current for operating the motor or other devices on the car. The sections of working conductor, preferably, lap upon one another at their abutting ends, as shown in the plan Fig. 2, so that there shall be no break of electrical continuity in the passage of the wheel W, across the joints where the ends of the sections are insulated from one another.

H, is an armature permanently or continuously magnetized and serving when actuated by either of the magnets B, on the car, to operate the circuit closer which connects the section of working conductor to the supply line L, Fig. 1. The circuit closer may be the armature itself which is pivotally supported at one end on the pole of an electro-magnet E, and at its free end engages, when raised

with a part in electrical connection with the plate A, thus closing the electrical connection to the supply wire by way of the support for the armature coil 20, for electro-magnet E, 5 and wire m. Other connections are at the same time established by way of the core of the magnet E, and wire n, to the same supply wire through coils 21, 22, of magnets E', at other sections removed; in the present case 10 two or other number of sections to the front and rear of the active section. The office of the coils 21, 22, is to reset the switches of other sections, when set, to the normal position or position opposite that in which they 15 are placed by the action of a magnet B. The office of the coil 20, is to strongly polarize the armature H, and insure good connection of the circuit closure. The armature H, is preferably of steel. The coil 21, or 22, operates 20 through the core of electro-magnet E', or otherwise, with proper polarity to pull down the armature H, whose free N-polar end is arranged as shown over the S-pole of electro-magnet E', but is kept out of actual contact 25 therewith by interposed non-magnetic material F. Electro-magnets E', also serve to hold the armatures down and prevent them from being accidentally drawn up by their own magnetism when subjected to heavy vibration or jamming.

The direction of the current in the several coils is indicated by the arrow heads. On the under side of the plate A, are strips of soft iron g, g, connected to plugs C, also of soft 30 iron which serve to carry the magnetism of magnets B, through the cover plate and by strips g, localize it over the free polar end of the armature H. The plugs C, are preferably set in bushings C', of non-magnetic material 35 like brass to prevent dissipation of the magnetism in the cover plate A, of iron. The free ends of the strips g, g, may be supported by brass rivets or pins a.

Two magnets B, are shown and both may 40 be energized at the same time from the circuit on the car in any desired way and both have like poles presented to the armatures. If the car is proceeding in the direction of the arrow the one at the left is the one that 45 operates. In moving in the opposite direction, the other operates. It is obvious that while proceeding in one direction the rear magnet might be rendered inactive, if desired.

In the diagram Fig. 1, R, is any source of 50 electric power, and T, the rail or conductor between which and main line L, the connection is completed and broken section by section as the car proceeds in either direction. Six sections of working conductor are shown.

55 The general operation is as follows:—Assuming that the car is moving from right to left, and that the magnet B, thereon passes onto section 4, the collector being in connection with section 5, next in the rear, when the magnet reaches the first plug C, it magnetizes the same and through the soft iron strip g, acts on the permanent magnet H, thereby

closing the connections for section 4, so that when the collector reaches said section the latter will be alive. When circuit is closed 70 at 4, by the collector reaching said section, which it immediately does, current flows also by way of its circuit closer through a coil 21, of section 6, and a coil 22 of section 2, and in such direction that the armature of the section is positively moved downward by the action of electro-magnet E', and is thereby pulled away from contact with the soft iron g, against which it was held by permanent magnetism although the collector had left section 6, and thereby broken the connection of coil 20 at such section. At section 2, no effect will be produced unless the armature shall have been accidentally raised or unless the car shall have left said section in proceeding in the opposite direction. The attraction of armature H, at section 4, and the contact of the collector with the working conductor, as just stated, also bring into action the coil 20, which operates to insure the continuance 80 of the switch in circuit closing position while the car is passing on the section, and also gives the steel magnet a permanent charge which keeps it up until positively drawn down again by the action of coil 21, when the car 85 reaches section 2. As will be seen the collector in leaving section 5, breaks no electric circuit because section 5, remains alive until the car passes along far enough to cause the coil 21, of section 5, to become active. The same 90 operation takes place when the car passes onto section 3, but the armature of section 5, is reset by the current which flows to it from the working conductors of section 3, and through the coil on magnet E', and the coil 95 of magnet E', at section 1, is also rendered active. In proceeding in the opposite direction the same operation takes place, the closing of the circuit at each section serving to render active the coils of sections at front 100 and rear by which the switches are positively opened. These sections may, obviously, be separated by one or a greater number of sections, as desired, from the section from which the car is taking current. Under this 105 system each car will positively control sections both at front and rear of itself and cannot be approached by another car nearer than the distance covered by the controlled and any intermediate sections. This action would 110 be useful under some conditions though I contemplate in general the use of short sections and the having of a few only active at the same time. In moving in the opposite direction the other magnet B, which now becomes 115 the forward magnet operates on the armatures to close the circuits and the coil of magnets E', which were rendered active ahead of the car now operate behind it to reset the circuit 120 closers to normal position.

I do not limit myself to any particular construction of circuit closing devices or ways of arranging the several magnets and the armatures on the permanent way. Thus the coils

21, 22, might operate on the circuit closer in any other desired way to rest it though I prefer to have these act by means of a core E', upon the polarized armature H. It will be 5 obvious further that it is not material whether the armature operate by repulsion or by attraction in passing from either position to the other although for convenience of description I have assumed that in closing the circuit it is 10 attracted. The action of magnet E', may be either by attraction or repulsion according to its polarity or the polarity of that end or portion of the armature upon which it acts. In these matters it will be obvious to electricians 15 that the invention admits of many variations without departing from the general operation of the apparatus. So also the magnet B, could be made to act upon the armature on the permanent way through other constructions or 20 arrangements of intermediate soft iron pieces or such pieces might be even dispensed with.

What I claim as my invention is—

1. The combination with a magnet on the car and an armature therefor on the permanent way for closing the switch for one section, of a resetting magnet on the permanent way for opening the switch, energized by current flowing to another section when the car reaches the latter.
2. The combination of the magnet on the car, a polarized armature and switch for one section, and an electro-magnet on the permanent way for reversing the position of the polarized armature, said electro magnet being 35 in the circuit of another section.

3. The combination with each section, of working conductor, of resetting circuits closed simultaneously to sections both to the front and rear of said section and including at each such section the coils of an unset setting electro- 40 magnet.

4. The combination with a section of working conductor and a polarized circuit closer therefor, of an actuating magnet on the vehicle for setting the circuit closer, and an unsetting magnet connected with sections at both sides thereof. 45

5. The combination, with a section of working conductor, of a circuit closer, a polarized armature for actuating the same by the influence of a magnet on the car, an energizing coil for said armature in the circuit to said section, and a coil on the permanent way in a connection closed by the switch of another section for acting on said polarized armature 50 so as to open the circuit closer.

6. The combination with the working sections and switches therefor having armatures operated by a magnet on the car, of restoring magnets operating on said armatures and having two coils connected respectively to sections to front and rear. 60

Signed at Boston, in the county of Suffolk and State of Massachusetts, this 17th day of February, A. D. 1894.
